MESNE ASSIGNMENTS, TO THE PHINNEY ENGINEERING COMPANY, OF CHILLI-
COTHE, OHIO, A CORPORATION OF OHIO.

MACHINE FOR TRIMMING STRING-BEANS, &c.

1,193,935.

Specification of Letters Patent. Patented Aug. 8, 1916.

Application filed June 18, 1908. Serial No. 439,166.

To all whom it may concern:

Be it known that we, WILLIAM H. SMITH and CHARLES C. BROWN, citizens of the United States, and residents of Le Roy, in the county of Genesee and State of New York, have invented a new and useful Improvement in Machines for Trimming String-Beans, &c., of which the following is a specification.

This invention relates more particularly to a machine for trimming or cutting off the tip and butt ends of string beans, although the same may also be used for cutting off opposite ends of other articles, such as ears of corn, preparatory to husking the same, and the head and tails of fish before canning the same.

The object of this invention is to provide a simple and efficient machine whereby such cutting or trimming may be effected expeditiously and reliably.

In the accompanying drawings consisting of 2 sheets: Figure 1 is a side elevation of our improved trimming machine. Fig. 2 is a top plan view thereof. Fig. 3 is a vertical longitudinal sectional elevation of the machine. Figs. 4 and 5 are fragmentary vertical transverse sections taken in the correspondingly numbered lines in Fig. 3 and looking in opposite directions. Fig. 6 is a fragmentary horizontal section, on an enlarged scale, taken in line 6—6, Fig. 3. Fig. 7 is a fragmentary side elevation, partly in section, showing a modified construction of the means whereby the material is held while being operated upon by the cutter.

Similar letters of reference indicate corresponding parts throughout the several views.

A represents the main frame of the machine which may be of any suitable construction to properly support the working parts of the machine. Within the upper part of this frame is arranged an endless traveling belt or carrier B which extends longitudinally of the machine and has an upper operative part and a lower inoperative part movable lengthwise and horizontally in opposite directions in the main frame. This belt is preferably constructed of chain links and passes with its receiving and delivery sprocket wheels C, C' which are secured to horizontal receiving and delivery

shafts c, c' journaled at the rear and front ends of the frame. Motion may be imparted to this belt for moving the same in the direction of the arrow 1 in Fig. 3 by means of a driving pulley D secured to the delivery shaft c' and adapted to receive a driving belt.

On its outer side the carrying belt is provided with a plurality of pockets or holders E which are arranged in a row—side by side lengthwise of the direction of movement of the belt and secured transversely at intervals to the same. These pockets are preferably of concave form in cross section with the hollow side facing outwardly and have their ends open. The body of each pocket is preferably constructed of a piece of sheet metal which is bent into trough form and has its longitudinal edges e curled or rolled backwardly, as shown in Figs. 1 and 3, thereby stiffening these edges and avoiding the presentation of sharp shoulders against which the material to be trimmed is liable to be caught and interfere with alining the same in the pockets.

Any suitable means may be provided for delivering the material to be trimmed into the pockets at the receiving end of the carrier. The means for this purpose which are shown in the drawings as an example, consist of a supply hopper or box F secured to the front part of the frame and having a closed bottom f, side walls f' and front walls f'' while its top and front sides are open, an elevator adapted to lift the material from said hopper and consisting preferably of a forwardly-inclined endless belt G provided with wings or buckets, g and adapted to move with its operative rear part upwardly past the open front side of the hopper, and upper and lower supporting pulleys H, H' around which the delivery and receiving portions of the elevator belt pass. These pulleys are mounted on horizontal shafts h, h' which are journaled transversely in the side walls of the hopper and are driven by means of a belt I passing around pulleys i, i' on the shaft c' of the receiving sprocket wheel of the pocket carrier and the delivery shaft h of the elevator, as shown in Fig. 2.

As the operative side of the elevator belt moves upwardly past the open front side of the hopper, its buckets engage with the material in the same and lift parts thereof

successively from the hopper. Upon reaching the top of the delivery pulley H the material held by the buckets is discharged successively therefrom upon an incline chute 5 i^2 which is arranged between the front part of the elevator and the receiving part of the pocket carrier and which directs the material into the pockets at this place so that it lies lengthwise in the same or in a direction transverse to the line of movement of the carrier.

After the material has been deposited by the feed device into the pockets of the carrier, it is first moved laterally therein in one 10 direction, so that one end of the material projects beyond the respective end of the pockets preparatory to trimming or cutting off this end of the material. The preferred means for thus shifting the material laterally in the pockets shown in the drawings 15 comprise a rotatable brush J arranged above the path of the pockets and mounted on the horizontal shaft j which extends longitudinally of the machine and is journaled lengthwise in bearings on the main frame. The 20 bristles of this brush are preferably arranged spirally and the pitch or lead of the same is such that the lower parts of successive turns or convolutions of the bristles 25 engage with successive pockets of the carrier in the manner of a screw, as shown in Figs. 1, 2 and 3. The relative timing of the movement of the pocket carrier and the 30 shifting brush J is such that the pocket carrier moves forwardly at the same rate of progress as the spiral bristles of the brush, thereby causing the bristles to always engage firmly with the material in the pockets and prevent the same from being dragged or 35 deflected out of their normal operative position by the pockets.

In addition to the brush J an air blast is caused to impinge against the rear ends of the beans or other material in the pockets 40 and assist in moving the same laterally in the pockets in the same direction in which they are moved by the brush J. This air blast is preferably directed against the beans by means of a jet or nozzle J¹ arranged at the right side of the path of the 45 pockets and preferably adjacent to the rear end of the brush J and connected by a pipe P² with the outlet of a fan J², as shown in Figs. 1, 2, 4 and 6. This air blast operates 50 on the beans just before they reach the brush J, whereby any beans which are liable to escape the shifting action of the brush J and are susceptible to the action of an air blast are shifted in the same direction in 55 which the brush operates.

The extent which the material is permitted to project at one end beyond one end of the pockets while being shifted by the air blast from the nozzle J¹ and action of the shifting brush J is limited by a gage k which prefer-

ably consists of an upright plate secured to the frame lengthwise along the outer ends of the pockets adjacent to where the pockets are engaged by the shifting brush J. As the material is pushed laterally in the pockets 70 against the gage plate k the ends of the same are prevented from being lifted out of place by means of a retaining plate k¹ arranged lengthwise over the gage adjacent to the shifting brush J and projecting inwardly 75 over the adjacent ends of the pockets.

After the material thus engages the gage plate k the same is carried forwardly by the pockets beyond the brush J to a cutter or severing device which operates to remove or 80 cut off those ends of the material which project beyond the respective ends of the pockets. The preferred form of cutter for this purpose which is shown in the drawings consists of two rotatable blades l which 85 sweep in a vertical plane across the path of the material between the respective ends of the pockets and the adjacent gage k and which are mounted on a horizontal shaft L journaled transversely in the adjacent part 90 of the main frame. While being thus cut the material is held firmly against displacement in the pockets by means of a holding device which is arranged in front of the brush J and which is preferably constructed as 95 follows: M represents a plurality of horizontal presser bars or rollers which are arranged in an annular row transversely above the path of the pockets and which are pivoted at opposite ends in arms m radiating 100 from a horizontal shaft N which is journaled transversely on the upper part of the main frame. As the pockets move forwardly the holding rollers or members engage successively with the pockets and the 105 material in the same, thereby causing the material to be held in the pockets at the time one end of the same is being severed by the cutter. The bodily rotary movement of the holding members is effected solely by 110 engagement of the same with the pockets in the manner of chain and sprocket gearing, thereby dispensing with a separate drive for this purpose. In order to permit the holding members to automatically adjust themselves to the thickness or amount of material contained in the pockets, the same are supported so as to permit them to yield the required extent. One of the means for this 115 purpose is shown in Figs. 1 and 5 and consists in mounting the shaft N of the holders at its opposite ends in the vertical slots n of guides n¹ arranged on opposite sides of the frame and applying a yielding downward pressure on this shaft by means of 120 springs o connected at their lower ends with the frame while their upper ends are connected with eyes or rings o¹ embracing opposite ends of the shaft N.

Instead of the construction shown in 125

Figs. 1 and 5 for yieldingly holding the rollers in engagement with the pockets, that shown in Fig. 7 may be employed. In this last mentioned construction the shaft N^1 of the holding device is mounted in stationary bearings n^2 on the frame and each holding roller M^1 is mounted at its opposite ends in bearings n^3 which move in radial slots n^4 formed in supporting arms n^5 5 of the shaft N^1 and are yieldingly held in their outermost position by springs o^2 engaging these bearings. After one end of the material has been trimmed off in the manner described, the same is moved laterally in the 10 pockets or transversely to the direction of movement of the carrier by another laterally shifting device which is constructed substantially like the first shifting device and consists preferably of a rotary brush arranged lengthwise above the path of the pockets and beans therein and an air blast nozzle or jet P^1 arranged at the opposite side of the path of the pockets and preferably adjacent to the rear end of the brush P 15 and connected by a pipe P^3 with the outlet of the fan J^2 . The brush P as shown is mounted on a horizontal shaft p which extends longitudinally of the machine and is journaled lengthwise in bearings on the upper part of the main frame and provided with spirally arranged bristles which engage successively with the pockets and the material contained in the same in the manner of a screw thread. The rotation of the 20 second brush and the trend of its bristles is opposite to that of the first brush, so that the material engaged by the same is moved laterally into a position in which it projects beyond the opposite ends of the pockets and engages with a second gage plate k^2 arranged lengthwise opposite the ends of the pockets where the same are being operated on by the second air blast and brush. A second retaining plate q is also preferably provided which projects inwardly from the upper part of the second gage plate over the adjacent ends of the pockets adjacent to the place where the material is being engaged by the second brush so as to prevent the 25 respective ends of the material from rising or becoming displaced. After the material has been thus shifted toward the opposite ends of the pockets the projecting ends thereof are cut off by a cutter arranged in front of the brush P and consisting preferably of two rotatable blades r which sweep through the space between the opposite ends of the pockets and the second gage and are mounted on a horizontal shaft L^1 30 journaled transversely on the main frame. While the opposite ends of the material in the pockets are being cut off the same is held against displacement in the pockets by a holding device which is constructed substantially like the first holding device above 35 described and which preferably consists of an annular row of transverse rollers m^2 adapted to engage successively with the pockets and the material in the same while being engaged by the second cutter and mounted at opposite ends on arms m^1 radiating from a horizontal shaft N^2 which is journaled transversely in bearings on the upper part of the frame, said shaft being guided at its opposite ends in the vertical slots n^2 of guideways n^3 on opposite sides of the frame and yieldingly held in its depressed position by means of springs o^3 . The tip and butt ends which are cut off the beans or other material drop on opposite sides of the carrier while the trimmed material is discharged from the pockets at the front end of the machine, suitable receptacles for the trimmings and finished material being provided if desired. 40 Motion may be transmitted to the brushes by various means, those shown in the drawings consisting of transverse shafts V , V^1 journaled on the main frame and connected by bevel gearing v , v^1 with the brush shafts, 45 a belt W passing around pulleys w , w^1 on the shafts c , V and a cross belt X passing around pulleys x , x^1 on the shafts, V , V^1 , as shown in Figs. 1 and 2. The means for driving the cutters may also be varied, that 50 shown in the drawings being suitable for the purpose and consisting of a belt Y passing around pulleys y , y^1 on the cutter shafts and a belt Z passing around pulleys z^1 , z^2 on the shaft of the first cutter and the transverse shaft of the first brush. 55 We claim as our invention:

1. A machine for trimming the ends of articles comprising a plurality of movable pockets which are arranged in a row lengthwise of the line of movement thereof and which receive and support said articles in a position transversely to the line of movement of the pockets, a rotatable brush having its bristles arranged spirally and adapted to engage successively with the articles in the pockets for moving the same therein transversely to the line of movement of the pockets, and a cutter past which the articles are moved by said pockets for trimming off the ends of the articles. 60
2. A machine for trimming the ends of articles comprising a plurality of movable pockets which are arranged in a row lengthwise of the line of movement thereof and which receive and support said articles in a position transversely to the line of movement of the pockets, a rotatable brush having its bristles arranged spirally and adapted to engage successively with the articles in the pockets for moving the same therein transversely to the line of movement of the pockets so that said articles project beyond the end of said pockets, a gage for limiting the transverse movement of the articles in 65

- the pockets, and a cutter past which the articles are moved by said pockets for trimming off the ends of the articles.
3. A machine for trimming the ends of articles comprising a plurality of movable pockets which are arranged in a row lengthwise of the line of movement thereof and which receive and support said articles in a position transversely to the line of movement of the pockets, a rotatable brush having its bristles arranged spirally and adapted to engage successively with the articles in the pockets for moving the same therein transversely to the line of movement of the pockets so that said articles project beyond the end of said pockets, a gage for limiting the transverse movement of the articles in the pockets, a retaining plate arranged above the gage in line with said brush and projecting inwardly toward said pockets, and a cutter past which the articles are moved by said pockets for trimming off the ends of the articles.
4. A machine for trimming the ends of articles comprising a plurality of movable pockets which are arranged in a row lengthwise of the line of movement thereof and which receive and support said articles in a position transversely to the line of movement of the pockets, a rotatable brush having its bristles arranged spirally and adapted to engage successively with the articles in the pockets for moving the same therein transversely to the line of movement of the pockets, means for driving said brush comprising a longitudinal shaft to which the brush is secured and a transverse shaft connected by gearing with the brush shaft, and a cutter past which the articles are moved by said pockets for trimming off the ends of the articles.
5. A machine for trimming the ends of articles comprising a plurality of movable pockets which are arranged in a row lengthwise of the line of movement thereof and which are adapted to receive and support said articles in a position transversely to the line of movement of the pockets, means for shifting the articles in said pockets in a direction transversely to the line of movement of the pockets, a cutter past which said articles are moved by said pockets for trimming off the ends thereof, and means for holding the articles in said pockets while in the trimming position comprising a rotatable support and an annular series of rollers or bars mounted on said support and adapted to successively enter said pockets and engage with the articles therein.
6. A machine for trimming the ends of articles comprising a plurality of movable pockets which are arranged in a row lengthwise of the line of movement thereof and which are adapted to receive and support said articles in a position transversely to the line of movement of the pockets, means for shifting the articles in said pockets in a direction transversely to the line of movement of the pockets, a cutter past which said articles are moved by said pockets for trimming off the ends thereof, and means for holding the articles in said pockets while in the trimming position comprising a rotatable support and an annular series of rollers or bars mounted on said support and adapted to successively enter said pockets and engage with the articles therein.
7. A machine for trimming the ends of articles comprising a plurality of horizontal movable pockets which are arranged in a row lengthwise of the line of movement thereof and which are adapted to receive and support said articles in a position transversely to the line of movement of the pockets, rotatable means for shifting the articles laterally in one direction in said pockets, a cutter adapted to sever one end of the articles in the pockets while in this laterally shifted position, rotatable means for shifting the articles laterally in the opposite direction in said pockets, and a cutter adapted to sever the opposite end of said articles in the pockets while in the last mentioned laterally shifted position.
8. A machine for trimming the ends of articles comprising a plurality of horizontal movable pockets which are arranged in a row lengthwise of the line of movement thereof and which are adapted to receive and support said articles in a position transversely to the line of movement of the pockets, rotatable means for shifting the articles laterally in one direction in said pockets, a cutter adapted to sever one end of the articles in the pockets while in this laterally shifted position, rotatable means for shifting the articles laterally in the opposite direction in said pockets, a cutter adapted to sever the opposite end of said articles in the pockets while in the last mentioned laterally shifted position, and gages which limit the lateral movement of the articles in the pockets under the action of said rotatable means.
9. A machine for trimming the ends of articles comprising a plurality of horizontal movable pockets which are arranged in a row lengthwise of the line of movement thereof and which are adapted to receive and support said articles in a position transversely to the line of movement of the pockets, rotatable means for shifting the articles laterally in one direction in said pockets, a cutter adapted to sever one end of the articles in the pockets while in the laterally shifted position, rotatable means for shift-

ing the articles laterally in the opposite direction in said pockets, a cutter adapted to sever the opposite end of said articles in the pockets while in the last mentioned laterally shifted position, gages which limit the lateral movement of the articles in the pockets under the action of said rotatable means, and means for holding the articles against displacement in the pockets while the same are being operated on by the cutters.

10. A machine for trimming the ends of articles comprising a movable pocket adapted to receive and support the articles in a position transversely to the line of movement of the pockets, means for producing air pressure against the articles in the pocket for moving the same laterally therein, a rotatable brush arranged adjacent to said 15 air pressure producing means and operating to move the articles in the pocket laterally in the same direction in which they are moved by the air pressure, and a cutter adapted to cut off those ends of said articles 20 which are at the front of the same when moved by the air pressure and brush.

11. A machine of the class described including an endless series of channeled holding devices, cutting elements adjacent the 25 paths of the ends of said devices, and oppositely disposed means for directing jets of fluid under pressure successively into opposite ends of the holding devices.

12. The combination with a conveyer including channeled holding blocks, of nozzles for directing jets of fluid under pres-

sure successively into opposite ends of each channel, separate snipping elements adjacent the paths of the ends of the channels for engaging the contents of said channels when shifted by the jets, and means for maintaining the channels closed during the reception of the jets.

13. A machine of the character described comprising a support for the article to be operated on, fluid pressure means constructed and operating to first move said article transversely on said support in one direction and then transversely in the opposite direction, and cutters arranged to operate 40 successively on said article at opposite ends of its transverse movement under the action of said fluid pressure means.

14. A machine of the character described comprising a support for the article to be operated on, fluid pressure means constructed and operating to first move said article transversely on said support in one direction and then transversely in the opposite direction, means for successively arresting 45 said article at opposite ends of its transverse movement, and cutters arranged to operate successively on said article at opposite ends of its transverse movement under the action of said fluid pressure means.
